UNITED STATES PATENT OFFICE.

SIR JOHN FRANKLIN, OF BEAVER CITY, NEBRASKA.

MACHINE FOR MANUFACTURING FUEL.

1,356,759.

Specification of Letters Patent. Patented Oct. 26, 1920.

Application filed January 6, 1920. Serial No. 349,782.

To all whom it may concern:

Be it known that I, SIR JOHN FRANKLIN, a citizen of the United States, residing at Beaver City, in the county of Furnas and State of Nebraska, have invented certain new and useful Improvements in Machines for Manufacturing Fuel, of which the following is a specification, reference being had to the accompanying drawings.

10 This invention relates to an improved machine for the manufacture of a fuel, as a substitute for coal, to be made from straw, Russian thistle, corn stalks, weeds, hay and many other like materials.

15 One of the objects of the invention is to provide a machine of this kind, wherein means are provided for cutting or chopping the material, compressing the material, there being a suitable binder applied, for 20 causing the particles to adhere and remain in compact form and means for cutting the compact or compressed material in pieces for consumption in stoves, ranges and furnaces.

25 Another object of the invention is to provide a machine of this character including a plunger and means for operating the same, and a manually controlled clutch for throwing the operating means in and out of 30 gear with any suitable power which may be connected to the operating means.

A further object of the invention is to provide a safety device, to be actuated by a lever, which in turn operates a clutch and 35 adapted to be held in the path of the cutting mechanism while the clutch is in gear, thereby preventing the cutting or sewing mechanism from being actuated until the clutch is moved out of gear.

40 A still further object of the invention is the provision of yieldably supporting means at one end of a casing in which the material is compressed or packed, there being an indicator carried by the yieldably supported 45 means to coöperate with a dial so as to indicate the pressure brought to bear on the material when compressed into said casing.

50 While the design and construction at present illustrated and set forth is deemed preferable, it is obvious that as a result of a reduction of the invention to a more practical form for commercial purposes, the invention may be susceptible to changes and the right to these changes is claimed, provided they are comprehended within the 55 scope of what is claimed.

The invention comprises further features and combination of parts, as will be hereinafter set forth, shown in the drawings and claimed.

60 In the drawings:

Figure 1 is a view in side elevation of the improved machine for the manufacturing of fuel.

Fig. 2 is a plan view of the same with 65 parts of the clutch in section.

Fig. 3 is a sectional view on line 3—3 of Fig. 1, showing the plunger in the act of compressing the material into a casing.

Fig. 4 is a cross sectional view on line 70 4—4 of Fig. 3 showing the cutting mechanism.

Fig. 5 is an enlarged detail sectional view of the portion of the casing 10 showing another position of the plunger 11 in order to 75 show another position of the crude oil plunger.

Referring more especially to the drawings, 1 designates a frame, and in bearings of one end of the frame is a shaft 2. A 80 driving pulley 3 is mounted upon the shaft 2, and is engaged by a belt 4, adapted for connection with an engine or any other suitable power so that it may be transmitted to the pulley 3, which when in gear connection with the shaft 2, will transmit power to the shaft. The shaft 3 is formed in two axially aligned parts or sections, and the adjacent ends of these sections are provided with disks 5, which are spaced. Piv- 90

oted at 6 eccentrically between the disks is a pitman 7 which in turn is pivoted at 8 to one end of a plunger 11. This plunger 11 is mounted in a casing 10 which is mounted on the bed plate 9 of the frame, and rising upwardly from the casing 10 and connected thereto in any suitable manner is a hopper 12. This hopper 12 merges into a second hopper 13, which is preferably of the shape shown, though not necessarily, and mounted in the second hopper 13 is a pair of crushing rolls 14 and 15. One end of the shaft of the roll 14 has a pulley 16, which is engaged by a belt 17. When this belt 17 is operated motion will be imparted to the pulley 16 and thereby cause the rolls 14 and 15 to rotate toward each other, thereby crushing the material such as corn stalks, weeds, hay and the like. The shafts of the rolls 14 and 15 have intermeshing gears 18, 110 so that the rolls may rotate toward each other.

The casing 10 has a chamber 19, in which the plunger 11 operates. As the material from the hopper 13 drops into the hopper 12 and then into the chamber 19, the 5 plunger operates to compress this material into the chamber 19 and then into the final compressing chamber 20. The casing 12 has a transverse slide 21, which supports the crushed material, particularly at the 10 time when the plunger 11 is forced into the chamber 19. However, when the plunger 11 is withdrawn from the chamber 19, the slide 21 may be opened, allowing the material to drop or fall into the chamber. Where the 15 final compressing chamber joins the casing 10, a slot 22 is formed, for the reception of the circular saw blade 23. The circular saw blade is carried by an arbor 24, which is pivotally mounted upon a shaft 25, which is 20 mounted in bearings of the frame of the machine. A pulley 26 is rotatable on the shaft 25 and carries a beveled gear 27. The bevel gear 27 meshes with a beveled gear 26^a of the shaft 26^b which is mounted in 25 suitable bearings 26^c of the frame. The outer end of the arbor 24 has bearings for the reception of the saw blade shaft 28, which is provided with a pulley 29. A belt 30 travels about the pulleys 26 and 29 so that when power is transmitted to the pulley 26 through the medium of the beveled gear 27, motion will be imparted to the saw blade. The bearing of the frame of the machine, which carries the shaft 25 has an 35 extension 31 to which a coil spring 32 is connected. This spring 32 is in turn connected to the arbor 24, thereby tensioning the same and acting to hold the saw blade normally 40 out of engagement with the transversely disposed slot 22, which is located at a point between the casing 20 and the chamber 19. The extension 31 has an abutment lug 33 to limit the arbor in its normal position. A 45 foot engaging member or lever 34 is carried by the arbor and is located so as to be engaged by the foot of the operator for tilting the arbor pivotally upon the shaft 25, to move the saw blade through the slot of the frame, for the purpose of cutting the compressed material into parts for consumption in stoves, ranges and the like.

The casing having the chamber 20 comprises the top and bottom and side walls, 37, 38 and 39 which are hingedly united as at 50 40. The top wall 39 and the side wall 37 have suitable detachable connections 41, whereby the various parts of the casing 20 may be opened to permit the removal of the compressed material.

60 The open end 42 of the casing 20 is closed by an abutment 43. This abutment rests upon the shoulder 44 of the end of the frame 1, and passing through the abutment are guide screws 45, which are threaded at 65 46 in the frame 1. Springs 47 surround the

screws 45, and are interposed between the heads 48 of the screws and the abutment. By adjusting the screws 45 in one direction, the springs may be tensioned to hold the abutment in place, so that the upper part 70 thereof will close one end of the casing 20. Where the upper part of the abutment 43 closes the opened end of the casing, said abutment is provided with a shoulder 49 to engage and rest upon the frame 1. An indicator 50 is carried by the abutment, and coöperates with an arcuate dial 51, so that as the material in the casing 20 is compressed, the indicator will move over the dial, and indicate the pressure which is 80 brought to bear upon the material as it is compressed. The greater the amount of material which is forced into the casing 20, the greater the pressure, and by means of the indicator and the dial, the variations 85 of the pressure will be clearly disclosed on the dial.

A suitable receptacle 52 is mounted on the side of the hopper 13, and contains a suitable binder, there being a passage or 90 tube of communication 53 with the interior of the casing 20, so as to feed the liquid binder into the casing 20, so as to mix with and bind the parts of the material as they are compressed. As the material is bound, 95 and as it partly dries and hardens, it is cut in cubical forms by means of the circular saw 23. It is to be noted that as these cubical forms reach the open end 42 of the casing 20, and the abutment moves away 100 from the casing, owing to the pressure at the rear of the material, the cubical forms may be removed, one at a time, should it be so desired. However, the casing 20 may be 105 opened, as previously stated, to permit the material in cubical forms to be more quickly removed.

The pulley 3 is loosely mounted upon the shaft 2, and the web or the spokes of said pulley 3 have apertures 4, which receive 110 the clutch pins 54^a of the clutch 54^b. This clutch 54^b is also loose upon the shaft 2, and is capable of sliding movement axially on the shaft, but at the same time is always rotatable with the pulley 3, as the 115 clutch pins 54^a are at all times in engagement with the openings or apertures 54. The clutch member 54^b has clutch teeth 54^c which are designed to coöperate with the teeth 55 of the pulley 56, which is also 120 loose upon the shaft 2. This pulley 56 is prevented from axial movement relatively to the shaft 2. A lever 58 is pivoted at 59 to a part of the frame of the machine and is provided with forks 60, which pivotally 125 engage the lateral lugs 61 of the two-part collar 62, which is carried in the groove 63 of the clutch 54^b. The lever 58 is angular, as shown, though not necessarily, and pivoted to one of its arms 65 is a rod 66. 130

which in turn is pivoted at 67 to a lever 68. This lever 68 is pivotally mounted at 69 on the frame of the machine and is designed to be oscillated for moving the 5 clutch member out of engagement with the clutch teeth 55, so as to permit the pulley 56 to remain idle on the shaft 2. A rod 70 is pivotally connected to the lower end of the lever 68, and is mounted in guides 71. 10 The end of the rod 70 is designed to assume a position in the path of the foot engaging member or lever 34 of the arbor to prevent the arbor from being oscillated as long as the clutch pins 54^a are in engagement 15 with the openings 72 of the pulley 73, which is keyed at 74 to the shaft 2. The clutch 54^b is shown in a neutral position in Fig. 2. In fact its clutch pins are out 20 of engagement with the openings 72 of the pulley 73, and its teeth 54^c are out of engagement with the teeth 55 of the pulley 56, and in this case the rod 70 has its end out of the path of the foot engaging lever 34, and also the working parts of the 25 machine are at rest. However, when the clutch 54^b is moved so that its teeth 54^c will engage the teeth 55 of the pulley 56, motion will be imparted to the belt 75 (which passes about the pulley 76 on the 30 shaft 26^b) thereby transmitting power to the saw blade. It is obvious that when the clutch is so coöperating with the pulley 56, the rod 70 still has its end out of the path of the foot operated lever 34, therefore, the 35 lever 34 is free to be actuated, and when actuated, the arbor will be oscillated so as to move the saw blade transversely through the chamber 19. The lever 68 is moved to 40 engage the clutch 54^b from the teeth of the pulley 56, at the time that the plunger 11 is withdrawn from the chamber 19, which has reached substantially its full 45 rearward position, so that the arbor is free to be oscillated with the saw blade 23 contacting with the plunger which would obstruct the passage of the saw blade.

The belt 75 also passes about a pulley 77, which is mounted upon a stub shaft 78 of the frame of the machine. The belt 17 50 passes about the pulley 73, and when the clutch pins 54^a are protruded far enough through the openings 54 of the pulley 3 they will engage the openings or apertures 72 of the pulley 73, so as to impart movement to the belt 17 and thence to the pulley 16, which is carried upon the shaft 14^a of the crushing roll 14. When movement is so imparted to the belt 17, the crushing rolls 55 will be operated, thereby crushing the material so as to enter the hopper 12 in proper form to be dropped in the chamber 19. Also when the clutch pins 54^a are in engagement with the openings 72 of the pulley 73, the end of the rod 70 will be disposed in the path of the foot operated lever

34, which will prevent the arbor 24 from being oscillated. The pulley 3 and clutch 54^b are at all times revolving, and when shifted in one direction or the other, one or the other of the pulleys 56 and 73 is operated. 70

A crude oil tank 80 has a pipe of communication 81 with the casing 10, there being a valve 82 for controlling the flow of any suitable crude or other combustible oils 75 into said casing. The plunger 11 is hollow and has its nose 83 conically shaped, and formed concentrically with the plunger is a tubular stem 84. The interior of the stem 84 at one end receives a crude oil 80 plunger or piston 85, and its other end merges into branch ducts 86. The tubular stem has a laterally extending tubular extension 87 integrally connected with the wall of the plunger 11. In fact the passage 85 through the lateral extension 87 communicates with the interior of the casing 10. The pitman 7 has a lateral arm 88 to which a second pitman 89 is pivotally connected as at 90. The pitman 89 is in turn pivoted 90 at 91 to the crude oil plunger or piston 85. As will be observed, in Fig. 3, the plunger 11 is capable of sufficient movement rearwardly so as to cause the duct or opening in the extension 87 to register with the outlet end of the pipe 81 leading from the crude oil tank 80. It will also be noted that the plunger or piston 85 is also at the limit of its rearward movement, which will permit a charge of crude oil to enter the duct 95 100 or passage in the stem 84. When the plunger 11 moves forward, an additional rearward movement is imparted to the plunger 85, owing to the downward movement of the pin 6 connecting the two disks 105 110 5. By this additional rearward movement of the plunger 85, the supply of oil that may be in the duct or passage of the lateral extension 87 between its ends, is permitted to slowly enter the main passage or duct 115 of the stem 84. When the pin 6 is on its upward movement, from its extreme lower position, a slight forward movement is imparted to the plunger 85, causing the crude oil to be forced through the passage of the 120 stem 84 into the center of the material which is being compressed in the chamber 19. When the pin 6 is in the act of moving upward from a position in a plane horizontally forward of the shaft 2 to its extreme upper position, an additional forward movement is imparted to the plunger 85, acting to additionally force the crude oil into the material being compressed. However, when this latter movement is imparted to the plunger 85 the plunger 11 is moving rearwardly, to permit more material to enter the chamber 19. It is obvious 125 that when this is the case, the material which has been previously compressed is 130

allowed to expand slightly, hence will permit the supply of crude oil to more easily enter the material, particularly as a result of the additional movement of the 5 plunger 85.

The material such as thistles, corn stalks, weeds, hay, straw and the like is placed in the hopper 13, where it is crushed by the rolls, and is then deposited into the hopper 10 12, and is supported by the slide 21. However, when the plunger 11 is moved to a rearward position from under the hopper 12, the material will deposit and fall into the chamber 19, as a result of withdrawing 15 the slide 21, and when it enters the chamber 19 it is compressed and compacted by the plunger 11 and then forced into the casing 20.

As these operations are continued, the 20 binder or adhesive material from the passage 53 mixes with the material and binds the parts together. After the material is bound or partly compact and dried, it is cut into cubical forms and then removed 25 from the casing 20, and when these cubical forms are thoroughly dried they are then to be used as fuel.

While the fuel manufacturing machine has been shown and described as operating 30 horizontally, the frame being correspondingly arranged, it is obvious that it may be constructed in an upright position as well.

The invention having been set forth, what 35 is claimed as new and useful is:—

1. In a machine for the manufacture of fuel, the combination with a casing having a compress chamber in which the material is forced, of a plunger operable therein, and 40 a cutter for cutting the material into lengths, said cutting mechanism including a swinging arbor having a circular cutting saw, a member to be driven and being operatively connected with the plunger for reciprocating the same, means for driving the member to be driven, a pulley loosely mounted upon the member to be driven, a 45 clutch member rotatable with the means for driving the member and being axially on the member and with relation to said means, said loosely mounted pulley having operative connections with the cutting saw and provided with clutching means to be engaged by the first clutch for imparting 50 movement to the cutting saw, and a safety device actuated by the first clutch to move said device in the path of an element of the arbor to prevent the arbor from being oscillated and prevent the blade from being 55 moved in the path of the plunger.

2. In a machine for the manufacture of fuel, the combination with a casing provided with a compress chamber to receive the material to be compressed, of a plunger 60 operable in the chamber, a swinging cutter,

an element to be driven and having connections with the plunger and provided with a pair of loose pulleys, means for driving both pulleys, connections between one of the pulleys and the cutter for imparting 70 revolute movements to the cutter, a clutch member on the element and adapted to clutch with either one of the pulleys, means for shifting the clutch member to engage first one pulley and then the other, so that 75 the plunger may be first operated and then the cutter, and a safety device actuated by the clutch operating means to move in the path of a member of said cutter to prevent the same from operating across the path of 80 the plunger.

3. In a machine for the manufacture of fuel, the combination with a casing having a compress chamber, of a plunger operable therein to compress the material into said 85 chamber, means for cutting the material as it is compressed, means for permitting an introduction of a binder into the chamber for mixing with and binding the material, an abutment at the open outlet end for the 90 material, and means actuated by the abutment to indicate the pressure brought to bear on the material in the compress chamber and the second casing.

4. In a machine for the manufacture of 95 fuel, the combination with a compress chamber for the reception of material to be compressed, of a plunger operable in said chamber for compressing the material, a cutter for the material, said chamber having a discharge end and a spring tensioned 100 abutment for the discharge end, and an indicator actuated by the abutment to indicate the pressure brought to bear on the material.

5. In a machine for the manufacture of fuel, the combination with a compress chamber for the reception of material to be compressed, of a plunger operable in said chamber for compressing the material, a cutter for the material, said chamber having a discharge end and a spring tensioned abutment for the discharge end, an indicator actuated by the abutment to indicate the pressure brought to bear on the material, and 110 means operatively connected with the plunger and the cutting means and including a clutch device whereby the plunger is first operated and then the cutter, to prevent the latter from obstructing the path of the 115 former.

6. In a machine for the manufacture of fuel, the combination with a compress chamber for the reception of material to be compressed, of a plunger operable in said chamber for compressing the material, a cutter for the material, said chamber having a discharge end and a spring tensioned abutment for the discharge end, an indicator actuated by the abutment to indicate the 125 130

pressure brought to bear on the material, means operatively connected with the plunger and the cutting means and including a clutch device whereby the plunger is first 5 operated and then the cutter, to prevent the latter from obstructing the path of the former, a lever for actuating the clutch member, and a safety device actuated by the lever to be moved in the path of a member 10 of the cutting means to prevent the cutting means from actuating while the plunger is operating.

7. In a machine as set forth, the combination with a casing for the reception of material to be compressed for fuel, and provided with a compress chamber, of a plunger operable in said chamber for compressing the material, means for permitting of the introduction of a binder into the compress 20 chamber to mix with and bind the material, and means for cutting the compressed material into lengths to be used as fuel, means for forcing a supply of crude oil into the material as it is being compressed in the chamber, pressure indicator to indicate the pressure brought to bear on said material, and means actuated by the material to operate the indicator.

8. In a machine for the manufacture of fuel, the combination with a casing having a compress chamber, of a plunger operable therein, means for permitting the introduction of a binder in said chamber, and a cutter for cutting the material into lengths, 35 means for forcing a supply of crude oil into the material as it is being compressed in the chamber, an indicator to indicate the pressure brought to bear on the material, and means actuated by the material for operating said indicator.

9. In a machine for the manufacture of fuel, the combination with a casing having a compress chamber into which the material is compressed, of means for crushing the material prior to being compressed, a plunger operable in the compress chamber, means for permitting an introduction of a binder into the chamber, a cutting mechanism including a cutter for cutting the material 45 into lengths, a driven member operatively connected with the plunger for reciprocating the same, means loose upon the driven member and adapted to drive the same, a pulley keyed to the driven member and having operative connections with the crushing means, a second pulley loose upon the driven member being operatively connected to the cutting mechanism and provided with a clutch, and a second clutch 50 loose upon the driven member and movable axially with relation thereto and to the operating means which is loose upon the driven member, and adapted to engage the clutch of the loose pulley for driving the cutting mechanism, and devices slidably connecting the second clutch with the means which is loose upon the member so as to 55 move at all times with the loosely mounted means, said devices adapted to detachably engage the keyed pulley when the second clutch is shifted, for operating the crushing mechanism and the plunger when the clutch is shifted out of engagement with the clutch of the loose pulley, and a safety device 60 operatively connected with and operated by the second clutch to move the safety device in the path of a member of the arbor to prevent the actuation of the cutter of the cutting mechanism when the plunger and the crushing mechanism are operating.

10. In a machine for the manufacture of fuel, the combination with a casing having a compress chamber into which the material is compressed, of means for crushing the material prior to being compressed, a plunger operable in the compress chamber, 70 a cutting mechanism comprising an arbor and including a cutter for cutting the material into lengths, a driven member operatively connected with the plunger for reciprocating the same, means loose upon the driven member and adapted to drive the same, a pulley keyed to the driven member and having operative connections with the crushing means, a second pulley loose upon the driven member being operatively connected to the cutting mechanism and provided with a clutch, and a second clutch 75 loose upon the driven member and movable axially with relation thereto and to the operating means which is loose upon the driven member, and adapted to engage the clutch of the loose pulley for driving the cutting mechanism, and devices slidably connecting the second clutch with the means which is loose upon the member so as to 80 move at all times with the loosely mounted means, said devices adapted to detachably engage the keyed pulley when the second clutch is shifted, for operating the crushing mechanism and the plunger when the clutch is shifted out of engagement with the clutch of the loose pulley.

11. In a machine for the manufacture of fuel, the combination with a casing having a compress chamber, of a plunger operable therein to compress the material into said chamber, operating means for the plunger, a cutting mechanism for cutting the compressed material into lengths, 90 and means for rendering the operating means for the plunger inoperative while the cutting mechanism is being actuated.

12. In a machine for the manufacture of fuel, a casing having a compress chamber, a plunger operable therein to compress the material into said chamber, operating means for the plunger, a cutting mechanism for cutting the compressed material into lengths, 100 and means for rendering the operating means for the plunger inoperative while the cutting mechanism is being actuated.

13. In a machine for the manufacture of fuel, a casing having a compress chamber, a plunger operable therein to compress the material into said chamber, operating means for the plunger, a cutting mechanism for cutting the compressed material into lengths, 110 and means for rendering the operating means for the plunger inoperative while the cutting mechanism is being actuated.

means of the plunger inoperative while the cutting mechanism is being actuated, and an indicator actuated as the material is compressed to indicate the pressure brought to bear on the material.

13. In a machine for the manufacture of fuel, a casing having a compress chamber, a plunger operable therein, and an indicator to register the pressure brought to bear on the material.

14. In a machine for the manufacture of fuel, a casing having a compress chamber, a plunger operable therein, an indicator to register the pressure brought to bear on the

material, and means actuated by the material for operating the indicator.

15. In a machine for the manufacture of fuel, a casing having a compress chamber, a plunger operable therein, an indicator to register the pressure brought to bear on the material, and an abutment at one end of the compress chamber actuated by the material for operating the indicator whereby the indicator may register the pressure brought to bear on the material.

In testimony whereof I hereunto affix my signature.

SIR JOHN FRANKLIN.
